UNITED STATES PATENT OFFICE.

ELLIS F. EDGAR, OF WOODBRIDGE, NEW JERSEY.

TUBULAR BOILER.

SPECIFICATION forming part of Letters Patent No. 505,036, dated September 12, 1893.

Application filed September 21, 1892. Serial No. 446,399. (No model.)

To all whom it may concern:

Be it known that I, ELLIS F. EDGAR, a citizen of the United States of America, and a resident of Woodbridge, in the county of Middlesex and State of New Jersey, have invented certain new and useful Improvements in Tubular Boilers, of which the following is a specification, reference being had to the accompanying drawing, forming part of the same, which is a central vertical cross-sectional view of a boiler embodying my present invention.

The invention consists in the combinations of devices hereinafter claimed whereby as one result the upper ends of the tubes are protected from too fierce a heat and the durability of the boiler thereby increased, and, as another, its efficiency is increased and a greater proportion of the heat units in the fuel are utilized within the boiler.

My desire is to use what I call a heat accumulator, that is, a plate which I have devised which will not be destroyed by fire, which will be in the direct(straight line)path of the heat currents though not injuring the draft, and which preferably is composed of fire clay that it may become highly heated. It thereby causes what has been described as a molecular bombardment of the atoms of consuming fuel one upon another which greatly increases the heat within the boiler and furthermore results in the almost entire exhaustion from said atoms of their heat units within the space desired to be heated. So too it insures the impinging of the flame and heat upon the tube walls and utilizes it most efficiently for heating the surrounding water. If such a plate alone were arranged over the farther ends of the tubes they would be so highly heated above the water line, that they would speedily burn out or at least begin to leak. Now great heat is not especially desired above the water line. The task is to heat the water and I have therefore arranged a series of plates, one within each tube, at or about the level of the water line of the boiler, in the form of incombustible walls preferably conforming in shape to that of the interior of the tubes but a little smaller than the tubes thus leaving space for draft all around their edges, between the wall and interior

surface of the tube, the aggregate of cross area of such draft spaces being somewhere near the area of the draft exit, to prevent choking. I usually also set a second plate of similar material over the ends of all of the tubes, supported upon the tube sheet but with ample draft space between it and said tube sheet. It acts especially to work sharply the outer tubes, which is of advantage. 6c

In the drawing B, is the boiler having an exterior shell S, interior shell S', ashpit A, firebox F, doors D, D', grate G, crown sheet C, tubes T, tube sheet t, walls W, and w, the latter within the tubes, and supported by rods r, extending down from cross bars b, which extend across the upper ends of the tubes, cover c', and draft exit E, the steam space being of course, that part of the boiler above the water line and below the tube sheet. 70 The tubes are preferably of good size four inches or more in diameter and when four inches I find that walls w, about (3½) three and one half inches in diameter give good results. 75

What I claim, and desire to secure by Letters Patent, is—

1. In a tubular boiler, the combination of an outer shell, an inner shell, a firebox, a tube sheet at the fire box, a tube sheet at 80 the smoke box, a series of fire tubes extending from one to the other of said tube sheets and a series of incombustible walls located within and partially closing said tubes at or about the water line of the boiler, but 85 leaving draft spaces substantially at the side edges of said wall, substantially as and for the purpose set forth.

2. A tubular boiler provided with an incombustible wall located in the smoke box and 90 extending over the ends of the tubes at a distance therefrom, in combination with other incombustible walls located within the tubes at or about the water line and partially closing the same and draft spaces substantially 95 at the side edges of said walls, all substantially as set forth.

E. F. EDGAR.
